UNITED STATES PATENT OFFICE.

AMOS F. LADWIG AND CARL A. LARSON, OF WATERLOO, IOWA.

ANTIRATTLING FASTENING DEVICE.

Application filed May 21, 1925. Serial No. 31,884.

To all whom it may concern:

Be it known that we, AMOS F. LADWIG and CARL A. LARSON, citizens of the United States, residing at Waterloo, in the county 5 of Black Hawk and State of Iowa, have invented certain new and useful Improvements in Antirattling Fastening Devices, of which the following is a specification.

Our invention relates to improvements in 10 fastening devices, and the object of our improvement is to supply releasable locking means for apposed bodies, which means when locked are so positioned and relatively arranged as to be tightly connected and 15 therefore not loose to rattle about when the connected bodies are being transported to and fro, and our invention is therefore especially adapted for such a specific employment as in fastening a motor car hood and 20 the like.

It is to be understood, however, that changes in the precise embodiment of invention herein disclosed can be made within the scope of what is claimed herein without departing from the spirit of the invention, and 25 that the invention can be used for any purpose within the scope of its possibilities.

We have effected the above object by the 30 means which are hereinafter described and claimed, and which are illustrated in the accompanying drawings, in which Fig. 1 is a side elevation of our invention as employed to fasten releasably the hood of a motor car to its frame member, other parts of the car 35 being removed, and Fig. 2 is an end elevation of the parts shown in said Fig. 1. Fig. 3 is a side elevation of a simplified and modified form of our invention and Fig. 4 is an end elevation thereof, with the lower part of 40 the hasp broken away.

Similar numerals of reference denote similar parts throughout the several views.

In said Figs. 1 and 2, the numerals 1 and 2 respectively denote apposed portions of a 45 Ford car hood and its frame. The hood is mounted to be lifted swingingly upwardly from the frame 2. Upon the outer side face of the hood 1 a plate 3 is riveted and carries a flat staple 16 with transverse aperture 17 50 to slidely receive a bolt part 21, which part is offset from the main body 20 thereof with the latter slidely and rockingly mounted in a spaced pair of apertured bearing projections 18 also rigidly mounted on said plate. As shown in Fig. 2, the aperture 17 in the staple 16 is shaped to permit of a

limited scope of rocking movement of the bolt part 21, crank-like, this part 21 being offset farther from the plate 3 than the bolt part 20 to afford clearance below said part 60 21 for the apertured hasp 10 therebetween. The plate 3 has alined with the bolt part 20 a stop projection 19 to limit the sliding movement of the bolt in that direction.

The hasp 10 is flattened at its upper end 65 to contact with the plate 3 flatly and is then bent in an offset manner outwardly so as to have its main cylindrical body alined with and above a bolt 4 which traverses alined holes in the spaced flanges of the channel-bar 70 frame member 2 of the car. The upper part of the hasp 10 has a longitudinal aperture or slot 14 punched out, part of the material being removed and the remainder shaped to produce an outwardly projecting curvate 75 finger-piece 15. As shown in Fig. 2, the hasp is connected to the bolt 4 hingedly and also tensionally by the following connection. The lower part of the hasp is hollowed at 11 to receive a headed rod 9 therein surrounded by a coiled compression spring 13, and the spring is engaged between the head of the rod 9 and an inwardly directed fillet 12 on the hasp. The lower end of the rod 9 80 has an eye 8 rockingly mounted on a cross-bolt or pintle 6 which traverses alined holes in furcations 7 which are part of a cylinder 5. The upper end of said bolt 4 is seated in the hollow of the cylinder 5 and secured therein by a head on the bolt to permit of 85 rocking the cylinder on the bolt, while the connection at the pintle 6 provides a hinge on which the hasp 10 may be swung to and from the plate 3, and the spring 13 gives a tensioning device whereby the hasp can be 90 extended to permit it to pass its aperture 14 about the staple 16 to let the upper edge of the aperture engage a notch in the staple when the hasp is released and the spring reacts. The bolt part 20 has a pair of orificed 95 seats for the lock members 23, one member secured rockingly in one seat, the other removably seated slidely from the other seat, to allow the lock 22 to thereby be locked to the intermediate pair of fixed projections 105 18 when the bolt part 21 is seated in the aperture 17 of the staple 16. When the lock 22 is so locked in position to said projections 18, it may be slightly rocked downwardly together with the bolt 20—21. On the padlock 22 is fixed one end of a spring snap or catch 24. The lower part of the plate 3 is

bent outwardly with a reversed curve and has along its lower edge a narrow flange 25 directed toward the plate 3. When the padlock 22 is pushed rockingly downwards, its 5 spring catch member 24 will pass yieldingly about said flange so that its upwardly bent tip will grasp the flange edge and thus releasably engage the padlock therewith, whereby the lock is prevented from swinging 10 loosely or knocking and disagreeably rattling while the car is rapidly moving or jolting over uneven surfaces.

In Figs. 3 and 4 is illustrated a simplified modification of the invention, wherein a 15 padlock 22' has its looped bolt member 23' passed through an aperture 17' in the staple 16' after the apertured hasp 10 is mounted upon the staple. In order to prevent loose 20 rattling of the padlock, a spring bar 27 has one end fixed to the plate 3 spaced from the under edge of the staple 16', and is carried thence curvingly near the staple edge and 25 upwardly to have its upper inwardly bent end or terminal 29 inserted movably in a slit 30 in the staple. This permits the bar 27 to resiliently yield toward the staple. The middle part of this bar 27 is concaved at 28. The padlock body is at opposite upper angles medially notched at 26, whereby 30 when the padlock is swung down, the notches 26 receive the bar 27 to prevent looseness or play sidewise, while compressing the spring bar until passing into the concavity 28 thereof, the bar binding and holding the 35 padlock tightly to prevent its rattling. When the padlock is swung upwardly, it is easily released from the spring bar 27, the clearance in the slit 30 permitting inward movement of the bar terminal 29.

40 This device with any needed change can be used on other cars than the type mentioned, as also in securing any other apposed objects together separably.

Having described our invention, what we 45 claim as new, and desire to secure by Letters Patent, is:

1. A device of the character described, comprising the combination with separable objects, of an apertured projection fixed on 50 one object, a hasp connected to the other ob-

ject and apertured to receive said projection, an apertured bearing-body fixed on the first-mentioned object, a bolt mounted slidably in said bearing-body to removably traverse the aperture of said projection to lock the hasp thereon, and means for releasably locking said bolt in engagement with said projection to also lock said hasp therewith.

2. A device of the character described, comprising the combination with separable objects, of an apertured projection fixed on one object, a hasp hingedly tensionally connected to the other object and apertured to receive and releasably tensionally interlock with said projection, an apertured bearing-body fixed on the first-mentioned object, a bolt mounted slidably in said bearing-body to removably traverse the aperture of said projection to lock the hasp thereon, and means for releasably locking said bolt in 60 engagement with said projection.

3. A device of the character described, comprising the combination with separable objects, of an apertured projection fixed on one object, a hasp connected movably to the other object and apertured to receive said projection, an apertured bearing-body fixed on the first mentioned object, a bolt mounted slidably in said bearing-body to removably traverse the aperture of said projection to lock the hasp thereon, engaging-means on the first-mentioned object, and releasable locking-means for locking said bolt in engagement with said projection and in releasable cushioning tensional engagement with 70 said engaging-means.

4. In a device of the character described, a staple, a hasp apertured to receive the staple, a padlock having a bolt member to be releasably connected interlockingly with 75 said staple, and a tensioning spring device engaged by and operative on said padlock to hold it releasably and without relative movements when the padlock is positioned to lock said hasp to said staple.

In testimony whereof we affix our signatures.

AMOS F. LADWIG.
CARL A. LARSON.
